(57) **CLAIM**

The ornamental design for a portable wheel chock, as shown and described.

DESCRIPTION

FIG. 1 is a top, front perspective view of a portable wheel chock as constructed in accordance with a first embodiment of the present invention;

FIG. 2 is a right side elevational view of the first embodiment, the phantom line showing of the wheel being for illustrative purposes only and forming no part of the claimed design;

FIG. 3 is a top plan view of the first embodiment;

FIG. 4 is a front elevational view of the first embodiment;

FIG. 5 is a left side elevational view of the first embodiment;

FIG. 6 is a rear elevational view of the first embodiment;

FIG. 7 is a bottom plan view of the first embodiment;

FIG. 8 is a top, front perspective view of a portable wheel chock constructed in accordance with a second embodiment of the present invention;

FIG. 9 is a right side elevational view of the second embodiment, the phantom line showing of the wheel being for illustrative purposes only and forming no part of the claimed design;

FIG. 10 is a top plan view of the second embodiment;

FIG. 11 is a front elevational view of the second embodiment;

FIG. 12 is a left side elevational view of the second embodiment;

FIG. 13 is a rear elevational view of the second embodiment; and,

FIG. 14 is a bottom plan view of the second embodiment.
